(57) **CLAIM**

I claim the ornamental design for a chair, as shown.

DESCRIPTION

FIG. 1 is a front perspective view of a chair showing my new design;

FIG. 2 is a rear perspective view thereof;

FIG. 3 is a front elevational view thereof;

FIG. 4 is a right side view thereof;

FIG. 5 is a top plan view thereof;

FIG. 6 is a rear elevational view thereof; and,

FIG. 7 is a bottom plan view thereof.

The fragmented depiction of the meshed pattern shown on the backrest and the seat is understood to repeat uniformly throughout the circumscribed areas.

1 Claim, 4 Drawing Sheets
